Philip Scamperle & Co. Kennedy

UNITED STATES PATENT OFFICE.

OTTO HAENTJENS, OF NEWARK, NEW JERSEY, ASSIGNOR, BY MESNE ASSIGNMENTS,
TO WORTHINGTON PUMP AND MACHINERY CORPORATION, OF NEW YORK, N. Y., A
CORPORATION OF VIRGINIA.

CENTRIFUGAL PUMP.

1,263,663.

Specification of Letters Patent. Patented Apr. 23, 1918.

Application filed October 29, 1915. Serial No. 58,700.

To all whom it may concern:

Be it known that I, OTTO HAENTJENS, a subject of the Emperor of Germany, residing at Newark, county of Essex, and State of New Jersey, have invented certain new and useful Improvements in Centrifugal Pumps, fully described and represented in the following specification and the accompanying drawings, forming a part of the same.

10 This invention relates to an improved two-stage centrifugal pump of the volute type with the impellers arranged back to back, the especial object being to produce a pump of this class, which shall be of high efficiency and in which the fluid shall make no sharp turns and the velocity of the water shall be gradually reduced and transformed to pressure between the first and second stages.

20 In the accompanying drawings forming a part of this specification, there is shown for the purpose of illustration a two-stage centrifugal pump of the preferred form embodying all the features of the invention, 25 and this pump will now be described in detail and the features forming the invention then specifically pointed out in the claims.

In the drawings—

Figure 1 is a vertical central section of 30 the pump.

Fig. 2 is a plan view of the lower half of the casing with the impellers and their shaft removed; and

Fig. 3 is a sectional elevation on line 3—3 35 of Fig. 1.

Referring to the drawings, A, A' are respectively the first and second stage impellers carried by shaft B, these impellers being reversed so as to balance the pump. 40 The casing is shown as divided on a horizontal plane into a lower section C and an upper section D, each carrying a portion of the partition E separating the impeller chambers, these sections being bolted together to form the casing and the lower section C carrying the suction and discharge passages F, G, with the flanged connection ends. The shaft B is mounted between the two sections C and D, with bearings in the 50 partition E and the casing walls. Delivery volute 1 from the first stage develops into a discharge passage 2 leading tangentially downward and gradually enlarging in cross section, and continued by a cross passage 3

under the discharge volute 4 of the second stage and then curving upward to the eye of the second impeller. The volutes 1 and 4 are set about 50 degrees apart, which has been found to produce the smoothest and most efficient flow and to best provide for the suction and discharge connections from the lower section of the casing.

It will be seen that this invention provides a very compact and efficient pump through which there is a smooth and even flow, and with the split casing shown, having its suction and discharge passages and the passage connecting the two stages formed in the lower section, results in a very light weight upper casting which is important for easy removal.

What I claim is.

1. A centrifugal pump having two single suction impellers arranged back to back with their single suctions in opposite directions and with volute deliveries and a passage connecting the discharge volute of the first stage with the suction of the second stage, said discharge passage running tangentially from the first discharge volute in gradually increasing cross-section to gradually reduce the velocity of the fluid and transform it into pressure and then transversely under the volute delivery of the second stage, and upward to the eye of the second impeller. 85

2. A centrifugal pump having two single suction impellers arranged back to back with their single suctions in opposite directions and with volute deliveries, a passage connecting the discharge volute of the first stage with the suction of the second stage, said discharge passage running tangentially downward from the first discharge volute in gradually increasing cross-section to gradually reduce the velocity of the fluid and transform it into pressure and then transversely under the volute delivery of the second stage and upward to the eye of the second impeller, and a casing formed in two sections cut on a horizontal plane, the lower section carrying the suction and discharge passages. 90

3. A centrifugal pump having two single suction impellers arranged back to back with their single suctions in opposite directions and with volute deliveries, a passage connecting the discharge volute of the first stage with the suction of the second stage, 105

said discharge passage running tangentially downward from the first discharge volute in gradually increasing cross section to gradually reduce the velocity of the fluid and 5 transform it into pressure and then transversely under the volute delivery of the second stage and upward to the eye of the second impeller, and a casing formed in two 10 sections cut on a horizontal plane, the lower section carrying the suction and discharge passages, the volutes being arranged for the flow of the liquid in the same direction and

with the terminals of both volutes in the lower section and the terminal of the first stage volute about 50° behind the terminal 15 of the second stage volute.

In testimony whereof, I have hereunto set my hand, in the presence of two subscribing witnesses.

OTTO HAENTJENS.
